UNITED STATES PATENT OFFICE

LOUIS S. PORTER, OF BROOKLYN, NEW YORK

CLOTHES HANGER

Application filed May 18, 1928. Serial No. 278,674.

This invention relates to improvements in clothes hangers and has for one of its objects to provide an improved hanger of simple and practical construction which is capable of being folded into compact form when not in use, and easily and quickly extended to its operative position.

Another object is to provide the hanger with a supporting hook in which is slidably mounted a latch member movable to a position wherein the same cooperates with a portion of the hook to encircle a supporting rod to prevent accidental detachment of the hanger from the rod.

The above and other objects will appear more clearly from the following detailed description when taken in connection with the accompanying drawing, which illustrates a preferred embodiment of the inventive idea.

In the drawings:

Fig. 1 is an elevation, partly broken away and shown in section, of the hanger in its operative position,

Fig. 2 is an elevation showing the hanger in partly folded position,

Fig. 3 is a similar view showing the parts completely folded.

Fig. 4 is a top plan view of the hanger as shown in Fig. 1, and

Fig. 5 is a section on the line 5—5 of Fig. 2, with the auxiliary hanger arm in extended position.

Referring more particularly to the accompanying drawing, the numeral 6 indicates a center plate from which extends the hook 7 having a portion offset from the plate, as best indicated in Fig. 4, the hook terminating in an arcuate portion 8 for suspending the hanger from a supporting rod or the like.

Slidably mounted in the portion 8 of the hook is an arcuate latch member, having a projection 10 adapted to be engaged to move the latch member from the position shown in Fig. 2 to that in Fig. 1 wherein said portion 8 and latch member combine to completely encircle a supporting rod to prevent accidental detachment of the hanger from said rod.

Pivoted to the center plate 6, on opposite sides of the shank of the hook 7, are the two complementary inner arms 11, each of channel

formation. Each of the arms 11 has pivoted to its outer end an outer arm 12, the inner end of which is adapted to be supported by the outer end of the arm 11 when the arms are in extended position, as shown in Fig. 1. When folding the hanger, the arms 12 are first swung about their pivots and recessed within the arms 11, after which the latter arms may be swung about their pivots to position, the same as shown in Fig. 3.

The arms 11 and 12 are provided respectively in their upper edges with notches 13 and 14, which are adapted to receive the shoulder straps of evening gowns, for instance, when suspending a dress from the hanger, said notches preventing the straps from slipping from the arms.

Either one or both of the arms 11, or if desired, the arms 12, may be provided with an auxiliary hanger arm 15, pivoted at 16 to the arm 11 for movement to an extended position shown in Fig. 5, and recessed, when in normal position, within the opening 17 formed in said arm 11.

What is claimed is:

A clothes hanger including a center plate, arms pivoted to said plate and extensible on opposite sides thereof, one of said arms having a recess in a side face thereof extending longitudinally of the arm from a point adjacent the pivotal connection thereof with said plate, and an auxiliary arm having one end pivoted to the first named arm and movable about its pivot from a nested position within said recess to a laterally extending position relative to said first-named arm.

In testimony whereof I have affixed my signature.
